UNITED STATES PATENT OFFICE.

HUGH B. BRADY, OF COBB, OKLAHOMA TERRITORY.

TYPE-WRITER ATTACHMENT.

SPECIFICATION forming part of Letters Patent No. 653,787, dated July 17, 1900.

Application filed February 3, 1900. Serial No. 3,811. (No model.)

To all whom it may concern:

Be it known that I, HUGH B. BRADY, a citizen of the United States, residing at Cobb, in the county of I, and Territory of Oklahoma, 5 have invented a new and useful Type-Writer Attachment, of which the following is a specification.

My invention relates to paper-roll attachments for type-writing machines; and my object is to produce a simple, strong, durable, and cheap device applicable to any of the approved forms of type-writing machines of that class, whereby the paper is always ready for use, enabling the operator to avoid the loss 10 of time it takes to change paper, permitting him (if a receiving-operator) to clear one office without changing the paper—an important item where the work is heavy, particularly 15 for operators stationed along the line of a railroad.

Other objects of the invention will hereinafter appear, and be pointed out in the appended claims, and in order that it may be fully understood reference is to be had to the 20 accompanying drawings, in which—

Figure 1 is a top plan view of an attachment embodying my invention. Fig. 2 is a front view of the same. Fig. 3 is a vertical cross-section of the same. Fig. 4 is a detail perspective view of one of the winding-shafts. Fig. 5 is an enlarged vertical section of part 30 of the attachment-frame as applied and secured to a bar of the platen-carriage. Fig. 6 is a detail perspective view of the construction shown in Fig. 5. Fig. 7 is a side elevation, partly broken away, of one end of the frame to expose the ratchet-tooth side of one of the friction-disks and the pawl to prevent back rotation of the same.

Referring to the drawings, where like reference-numerals designate corresponding parts, an inverted-U-shaped frame (see Fig. 2) comprises the upper portion 1, and at the lower ends of the same the forwardly and rearwardly 45 projecting angle-arms 2, terminating in foot-plates 3, adapted to underlie and bear tightly against the front and rear bars 4 of the carriage-frame of a Remington, Smith Premier, or any other approved type of machine, and 50 the pendent portions of angle-arms 2 are formed at their inner edge with a series of ratchet-teeth 5.

6 designates clamp-plates slidingly mounted on the pendent portions of the attachment-frame, provided with upwardly-projecting 55 ears 7, between which are pivotally mounted dogs 8 for engagement with teeth 5, and in order to trip said dogs from such engagement they are provided with arms 9 to receive the downward pressure of the operator's thumb 60 or finger. To lock each dog against accidental movement from its operative or inoperative position, it is provided with notches 10 and 11 to receive the bevel-tooth 13 of the spring 12, arranged between the ears and riveted to 65 the clamp-plate. In order that the attachment-frame may be secured rigidly and reliably to bars 4, irrespective of the thickness of the latter, the clamp-plates carry at their under sides the stiff springs 14, bowed down 70 to bear upon the bars and having their free or movable ends bifurcated, as at 15, to embrace the guide-pin 16, depending from the clamp-plates. By this arrangement it is obvious that as the attachment-frame is fitted, 75 for instance, to a Remington, as indicated by the style of bars 4, with the foot-plates 3 underlapping said bars, the clamp-plates are slid down upon the pendent portions of the frame until the springs or cushions 14 are 80 brought to bear upon bars 4 with sufficient force to clamp the foot-plates tightly and rigidly up against said bars, the springs 12 yielding sufficiently to permit the dogs 8 to slide from tooth to tooth in their progress downward and automatically locking them when 85 the downward pressure upon the clamp-plates is removed.

When it is desired to remove the attachment-frame, it is only necessary, by pressing 90 downward upon arms 9, to trip the dogs 8 and permit teeth 13, by engagement with notches 11, to lock the dogs in their inoperative position, leaving the clamp-plates free to slide upward and the frame to be removed from 95 the machine.

Projecting upward from the forward angle-arms 2 are short arms 17, carrying at their upper ends the connecting paper-guide bar 18 and the paper-cutting knife 19, the latter 100 also extending from one arm 17 to the other and converging with respect to bar 18, providing a sharpened upper edge upon which the paper containing the copy to be mailed

or forwarded to another point may be severed at any time.

The vertical arms of the upper portion are provided in their front edges with the forwardly and upwardly inclined bearing-notches 20, 21, 22, 23, and 24, and journaled in notches 24 is the shaft of paper-roll 25, designed as the copy to be mailed or forwarded. Journaled in notches 23 is the shaft of carbon-paper roll 26, and journaled in notches 22 is the shaft of record-paper roll 27. Journaled in notches 21 is a shaft 28, designed to receive and act as a winding-roll for the carbon-paper, and said shaft is provided with a longitudinal slot or groove 29, intersected near one end by a notch 30 in the shaft for a purpose which will hereinafter appear and registering at the contiguous end with the inclined notch 32 in the inner face of a circular enlargement or disk 31, forming a part of the shaft, the enlargement or disk 31 at the opposite end of the shaft having a hole 33, in which is secured the spring-rod 34, said rod fitting in the groove 29 and having its lower end projecting into notch 32. When it is desired to attach the front end of the carbon-sheet to said shaft, the operator inserting his thumb or finger in notch 30 springs the rod 34 upward and out of notch 32 sufficiently to interpose the end of the carbon-sheet between the shaft and rod. He then releases the latter, and as it snaps back in position it presses the sheet firmly down into the groove 29, and thus eliminates all chance of the paper slipping as the roll begins to wind. In practice it will be advisable for economical reasons to employ a similar shaft for notches 23, to the end that the carbon-rolls shall be interchangeable—that is to say, when the paper on roll 26 is entirely wound upon roll 28 the shafts may be interchanged, shaft 28 in notches 23 to act as the feeding-roll and the other similar shaft in notches 21 to act as the winding-roll, as will be readily understood.

28^a designates a shaft journaled in notches 20, similar in form to shaft 28, with the single exception that it is more prolonged at one end, as shown in Fig. 2, and to this shaft is adapted to be secured the front end of the record-sheet.

Vertically below shaft 28^a and projecting inward from the attachment-frame are stub-shafts 35, upon which are journaled friction-rollers 36, meshing at their upper sides with the friction-disks 31 of shaft 28^a and at their lower sides with the friction-bands 38 upon the ends of the platen 37, said bands in practice being preferably secured to the circular end plates commonly found on the platen, as at 39. (See Fig. 2.)

In practice as the platen is revolved in the direction indicated by the adjacent arrow, Fig. 3, the three strands of paper paying out in the corresponding direction and at the same speed through the customary paper-feed roll 37^a or its equivalent the friction-disks 36 are rotated in the direction also indicated by

an arrow and impart rotary movement to the shaft 28 through the medium of its friction-disks 31. In order that the shafts 28^a and 28 shall move synchronously and at the same speed, I provide the following mechanism:

40 designates a sprocket-wheel upon the projecting end of shaft 28, (see Fig. 2,) and 41 a chain connecting said sprocket-wheel 75 with a sprocket-wheel 42, journaled on the prolonged end of shaft 28^a, and said sprocket-wheel 42 is provided with a toothed clutch member 43, normally engaged by the clutch member 44, keyed to slide but not rotate on the shaft 28^a, and said sliding clutch member is held yieldingly in engagement with clutch member 43 by means of the spring 45, surrounding the shaft and bearing at its opposite ends against the sliding clutch member 85 and the collar 46, rigidly secured on the shaft. By this construction it will be seen that motion is transmitted from shaft 28^a to shaft 28.

As the operator may desire to remove the day's business from off the record-paper-winding roll, it is necessary that provision be made whereby the shaft 28^a may be thrown out of gear with shaft 28 and the cylinder. To effect this, I provide means to disengage the clutch members, the same comprising a bearing-lug 47, projecting from the frame between the strands of the sprocket-chain, and a lever 48, pivoted to said lug and engaging the customary groove of the sliding clutch member in order that it may slide the latter on the 100 shaft without interfering with its rotatable action. To disengage the clutches, pressure is brought to bear upon the upper end of the lever, and in order to lock the clutches out of engagement the upper end of the lever is 105 formed with a hole 49, adapted to be engaged by a hook 50, pivoted to the frame. (See Fig. 2.) When the clutches are disengaged, it is obvious that the record-paper roll may be unwound without affecting the position of the carbon-paper-winding roll, and in order that the position of the platen shall not be affected the outer sides of the friction-disks 36 are provided with ratchet-teeth 36^a, engaged by spring-pawls 36^b, secured to the frame and 115 adapted to permit the disks to turn in the direction indicated by the arrow, Figs. 3 and 7, but not in the opposite direction, as will be readily understood.

Assuming that the attachment is mounted 120 upon the machine as indicated in Fig. 3 and that the strands from the feed-rolls 25, 26, and 27 extend up through the paper-cutting mechanism and to rolls 28 and 28^a, respectively, it is obvious that in the manipulation 125 of the machine the paper will be printed as usual and that each time the platen is turned to space for a new line the outer copy will be fed up past the cutting-knife, the carbon will be wound upon roll 28, and the record-copy 130 upon roll 28^a.

If at any time it be desired to remove the day's business from the record-paper-winding roll, it can be accomplished by first throw-

ing it out of gear with the carbon-paper-winding roll and the cylinder in the manner described. When all of the paper on the upper or feed rolls is unwound, they can be removed 5 readily by lifting them out of the notches in the frame, and the same is true of the carbon and record paper winding rolls. The latter may be filed away and the former fitted into notches 23 to be used again. New record and correspondence rolls are also fitted 10 into the proper notches and the three strands of paper properly adjusted around the platen and to the shafts 28 28^a and up through the knife, as will be readily understood. The 15 machine is now in condition for operation.

When the attachment is in position, it is unnecessary to reverse the movement of the platen; but when not in position said platen is free to be manipulated in the customary 20 manner.

While for convenience of illustration and to prevent the specification from being unnecessarily prolix I have shown and described only the particular method of construction 25 whereby the attachment is to be secured to one style of machine—viz., the Remington—it is to be understood, of course, that it may be with equal facility attached to the Smith Premier or other machines by varying the 30 construction at the lower end of the pendent portions of the angle-arms, and in order to cover such variations I have entered claims sufficiently generic for the purpose. It is to be understood also that various other changes 35 may be made in the form, proportion, detail construction, or arrangement of the parts without departing from the spirit and scope of the appended claims.

Having thus described the invention, what 40 I claim as new, and desire to secure by Letters Patent, is—

1. An attachment for type-writing machines, comprising a frame detachably mounted on the platen-frame of the machine, paper-feed rolls journaled in the attachment-frame, winding-rolls journaled in the attachment-frame and adapted to receive the paper from the paper-feed rolls after it has passed under 45 the platen, and geared together, friction-disks

journaled on the attachment-frame and engaging the platen and a winding-roll shaft, and means to prevent back rotation of said friction-disks, substantially as described. 50

2. An attachment for type-writing machines, comprising a frame detachably mounted 55 on the platen-frame of the machine, paper-feed rolls journaled in the attachment-frame, winding-rolls journaled in the attachment-frame and adapted to receive the paper from the paper-feed rolls after it has passed under 60 the platen and geared together, friction-disks journaled on the attachment-frame and engaging the platen and a winding-roll shaft, means to prevent back rotation of said friction-disks, and means to throw said winding-rolls out of gear, substantially as described. 65

3. In an attachment for type-writing machines, the combination of a pair of winding-roll shafts, a wheel mounted upon one of the said winding-roll shafts, a wheel journaled 70 upon the other and connected to the first-named wheel, and provided with a clutch-face, a spring-actuated sliding clutch member mounted on the second winding-roll shaft and adapted to engage and impart movement to 75 said clutch-face wheel, a lever to throw said clutches out of gear, and means to maintain them in such relation against the resistance of the spring-actuated clutch, substantially as described. 80

4. An attachment for type-writing machines, comprising a frame having foot-plates to bear against the platen-frame of the machine, and a vertical series of teeth, clamp-plates slidingly mounted on the frame to 85 move toward or from said foot-plates, and adapted to bear against the platen-frame at the opposite side from said foot-plates, dogs pivoted to said clamp-plates, and springs carried by the plates and adapted to hold the 90 dogs in or out of engagement with certain teeth of the frame, substantially as described.

In testimony whereof I affix my signature in the presence of two witnesses.

HUGH B. BRADY.
